C. E. Beach,

UNITED STATES PATENT OFFICE.

CLARENCE E. BEACH, OF BINGHAMTON, NEW YORK.

SIGNAL DEVICE.

Application filed December 7, 1920. Serial No. 428,970.

To all whom it may concern:

Be it known that I, CLARENCE E. BEACH, a citizen of the United States, residing at Binghamton, county of Broome, and State 5 of New York, have invented certain new and useful Improvements in Signal Devices, of which the following is a specification.

This invention relates to signal transmitting devices having releasing mechanism 10 variably operable to cause the transmission of signals of one or more cycles or "rounds," certain characteristics of some of such rounds being varied in a predetermined manner in other of such rounds.

15 The transmitting device of this invention is particularly adapted for use in signal systems such as, for example, automatic fire alarm systems in which distinctive warning signals should be given in response to the 20 development of various conditions such as; (1) in the event of certain transient conditions (for example, abnormal circuit or temperature conditions of comparatively short duration), with facilities for repetitions, 25 without any intervening manual attention, upon each recurrence of such transient conditions; (2) in the event of certain continuing conditions (for example, a broken line or a run-down motor-spring) for which, 30 in the absence of intervening manual restoration and after the transmission of the intended number of rounds, there should be no response to continuation, recurrence or repetition; or (3) in the event of certain 35 other continuing conditions (for example, the abnormal heat conditions incident to fire) to which a predetermined number of signal rounds should be transmitted even if the agency responsive to such conditions 40 ceases to be effective to maintain the releasing mechanism in operated condition throughout all of such rounds, but should not transmit an excessive number of rounds, even if such agency is continuously or 45 repeatedly conditioned to cause said releasing mechanism to assume its operated position after intended rounds have been transmitted.

Transmitting devices employed in such systems usually comprise trains which are 50 arranged to be set in action by means of magnetically operated releasing mechanism, and such trains have automatic controlling means moved by the running thereof and rendered effective by the co-operation of such magnetic releasing mechanism to stop 55 the train after the conclusion of a prede-

termined extent of continuous operation thereof. In prior devices such co-operation of the magnetic releasing mechanism has served to substantially increase the frictional load and has necessitated the employment of increased retractile stress opposing the magnetic pull, thus necessitating the use of a magnetic pull greatly in excess of that which would be necessary to control the 60 running of the train, were it not for the co-operation of the releasing mechanism with the controlling means.

For reasons well understood by those skilled in this art, it is desirable to minimize, to the utmost extent compatible with 70 mechanical stability during periods of magnetic de-energization, both the frictional load and the retractile stress opposing the magnetic pull.

75 Prior transmitting trains employed for giving distinctive warnings in response to various conditions, as hereinbefore pointed out, have either been employed in duplicate or else have been equipped with double 80 magnetic controlling structures applied to a single train. In either event such duplication increases the cost of manufacture and maintenance, besides providing objectionable complication; and, when double 85 magnetic controlling structure is applied to a single train, the limited available space prevents the employment of as effective magnetic structure as could be provided if the same space was occupied by a unitary 90 magnet structure.

An object of this invention is to provide an improved signal transmitting mechanism comprising a signaling train and a unitary magnetic structure variably operable for 95 effecting the transmission of distinctive signals.

Another object is to provide improved controlling means for the train of a signaling device, which means will be moved by 100 the running of such train and rendered effective by the co-operation of a part operable by an extraneous force and adapted to assume any of two or more positions during the running of such train, whereby such co-operation will not impede movement of such part to start said train when at rest, or when said train is at a stage of its operation at or immediately following which said part might act to arrest the running thereof. 105

110 Other objects are to provide signaling de-

vices which are more positive in action, which are less difficult and expensive to manufacture and keep in proper running order, and which are more readily convertible for the accomplishment of various differing functions for the attainment of which different types of similar devices have heretofore been employed.

Still other objects will be in part obvious and in part specifically pointed out in the following specification.

In applying this invention to a signaling train having a starting and stopping mechanism the effectiveness of which is governed by controlling means moved by the train in running; if it is desirable that the signaling train shall have a recurrent cycle of action, and that, when such train has entered upon any such cycle of action, its action shall proceed uninterruptedly until the completion thereof; a holder is provided for preventing action of the starting and stopping mechanism to stop the train during any such cycle. For example, when such a signaling train is employed for the operation of code signal transmitting means, such holder is arranged to render the starting and stopping mechanism ineffective to stop the train during the stages of operation thereof when interruption of a round or cycle of such code signal would result from such stoppage. For want of a better distinguishing designation, such holder will be hereinafter referred to as "a guide for rendering the starting and stopping means ineffective to stop the train during certain stages of the operation thereof" or words to that effect; but it should be distinctly understood that such use of the word "guide" is not intended to describe any specific form of such holder as the details of the construction of this feature form no part of this invention.

When it is desired to employ a signaling train, such as just described, for the formulation of code signals, suitable formulating mechanism (such as a code wheel and circuit controlling contacts) is so arranged with relation to such train that the formulation of the desired code signal will be accomplished a greater or less number of times, as determined by the starting and stopping mechanism of such train after each formulating cycle thereof.

The controlling means hereinbefore referred to is arranged to so govern the functions of the starting and stopping mechanism that, after predetermined action of said train, said mechanism will act to stop the running thereof regardless of the action of the actuating means or the force which is normally effective to operate the starting and stopping mechanism to permit said train to start, when at rest, or to continue running after the completion of any cycle of the operation thereof.

When signaling trains are employed in which the starting and stopping mechanism is operable in response to changes in the excitation of an electromagnet incident to variations in the current flow in a circuit connected therewith, the current path through the windings of such electromagnet includes contacts so operable by the controlling means that said magnet will be rendered unresponsive to such variations after such predetermined action of said train.

When such a signaling train is arranged for operation in response to action of an extraneous force through one or another of two avenues, if a different number of operating cycles of such train should result from the action of such force through one of such avenues than should result from the action of such force through the other of such avenues; the communication of such avenues with the actuating means for the starting and stopping mechanism is so governed by the controlling means that, after a predetermined one or more operating cycles of the train, such starting and stopping mechanism will be rendered unresponsive to the action of such force through one of such avenues, and so that, after a predetermined additional one or more operating cycles of said train, said mechanism will be rendered unresponsive to the action of such force through the other of said avenues. Thus, if the starting and stopping mechanism is operable in response to an extraneous electrical force, acting through one or another of two current paths or avenues to cause changes in the excitation of an electromagnet; contacts are included in such paths, and are so operable by the controlling means that, after a predetermined one or more operating cycles of the train, said magnet will be rendered unresponsive to variations to the current flow in one of said paths, and so that, after a predetermined additional one or more operating cycles of said train, said magnet will be rendered unresponsive to variations in the current flow in the other of said paths. If the starting and stopping mechanism is operable in response to an extraneous mechanical force acting through one or the other of two mechanical agencies, or through movement of a single agency in either one direction or the other, latches or other disconnecting means are provided, such means being operable by the controlling means so that, after a predetermined one or more operating cycles of the train, said mechanism will be rendered unresponsive to the movement of one of such agencies (or to the movement in one direction of such single agency, as the case may be) and so that after a predetermined additional one or more operating cycles of said train, said mechanism will be rendered unresponsive to 130

such other movement. Such an electromagnet, in the case of an electrical force, and a diaphragm or other structure responsive to such a mechanical force, constitute translating mechanism for operating the starting and stopping mechanism.

For certain classes of service, it is desirable that, after the signaling train has acted through a predetermined number of the operating cycles thereof in response to the application of an extraneous force through a certain avenue to the translating mechanism of the starting and stopping mechanism thereof, that the action of such train should be continued through an additional predetermined one or more cycles thereof, regardless of the continuity of the action of such extraneous force through such avenue.

In adapting this invention to such classes of service, the controlling means is so arranged that, after movement thereof incident to running of the train for a predetermined number of the operating cycles thereof, the starting and stopping mechanism will be rendered ineffective to stop the running of said train until after the completion of the desired number of additional operating cycles thereof. For example, when a signaling train arranged in accordance with this invention has starting and stopping mechanism operable in response to changes in the excitation of an electromagnet incident to variations in the current flow in a circuit connected therewith, the current path through the winding of such an electromagnet includes contacts so operable by the controlling means, that, after a predetermined one or more operating cycles of the train, connections will be established which will assure such circuit relationship of said electromagnet as will prevent action of the starting and stopping mechanism to stop the running of the train until after said train has acted for an additional predetermined number of the operating cycles thereof. If the starting and stopping mechanism of such a train is operable in response to a mechanical force acting through one or more agencies, such relative arrangement of the starting and stopping mechanism and the controlling means is provided that, after a predetermined one or more operating cycles of the train, the starting and stopping mechanism will be mechanically prevented, by the action of the controlling means, from acting to stop the running of the train, until such running has been continued for the desired additional operating cycles thereof.

From the foregoing it is apparent that such trains and the controlling means moved thereby, when provided with electromagnetically operable starting and stopping mechanism, provide electromagnetically controlled mechanism comprising means

for rendering such starting and stopping mechanism responsive to various current paths after various predetermined operating cycles of such train.

Under certain operating conditions, transmitting means is required which will formulate two different signals, and which means will render the formulation of one of such signals effective only after the transmitting means has acted to formulate the other of such signals a predetermined one or more times. When it is desired to employ an embodiment of this invention which is suited to such operating conditions, suitable formulating mechanism (such as two sets of formulating contacts independently operable by distinctively arranged code wheels) is suitable arranged with relation to a signaling train constructed and arranged as hereinbefore described, to the end that the running of such train will cause such formulating mechanism to act to formulate the desired two different signals. In cases when one of such signals should, when effectively formulated, serve as a prefix or a suffix for the other of such signals; such transmitting means is arranged for formulating such signals successively and in alternation. The effectiveness of the formulating means in formulating one or the other of such signals is governed by the controlling mechanism which is moved by the train in running. For example, when the formulating mechanism comprises two sets of independently operable formulating contacts; circuit controlling mechanism is provided for the current paths of such contacts, such mechanism being operable by the train-moved controlling means to render one of the sets of said formulating contacts effective only after the signaling train has completed its cycle of operation a predetermined one or more times.

From the foregoing it is apparent that, in the instance of electromagnetically controlled signaling mechanism arranged in accordance with this invention and having two sets of code signaling contacts, the controlling means moved by the train in running operates circuit controlling mechanism to variably govern the circuit relationships of formulating mechanism contacts and electromagnetically controlled mechanism.

Important features of this invention reside in the construction and arrangement of the train-moved controlling means of signaling trains, such as those hereinbefore referred to, whereby certain functions of such controlling means are accomplished after the associated train has acted without stopping for greater or lesser numbers of the formulating cycles thereof, but such functions are not accomplished after such train has acted for like numbers of the formulating cycles thereof with intervening stops.

In accordance with one of such features, such controlling means comprises step by step accumulation mechanism intermittently engaged by the train in running for actuation thereof in one direction; the movement of said mechanism in such direction being hereinafter referred to as "accumulative" movement thereof.

Such accumulation mechanism comprises 10 a member having teeth, together with means operable by the train in running for engaging such teeth to impart accumulative movement thereto; means being provided for constantly imparting a tendency to move such 15 toothed member in the opposite direction so as to tend to cancel or restore any accumulative movement which has been imparted thereto.

Such accumulation mechanism also comprises holding means which may, for example, consist of a ratchet dog or holding pawl adapted to ride upon and engage the teeth of the toothed member so as to serve as a holding means adapted to prevent accumulation 25 canceling or restoring movement thereof.

In accordance with a further feature of this invention, the junctions of the lifting and holding faces of the teeth of the member intermittently moved by the train and of 30 the holding pawl therefor are so relatively formed that the outer ends of the holding faces of such teeth will act as lifting faces for said pawl. To this end, the outer ends of the holding faces of such teeth may be 35 beveled so as to act as lifting faces for the pawl during canceling or restoring movement of the toothed member, the junctions of the lifting and holding faces of the pawl may be correspondingly beveled to like end, 40 or both the points of such teeth and the junctions of said faces of the pawl may be so beveled. In any event, such parts are 45 so relatively formed that the points of the teeth of said member will serve to lift the holding face of the pawl a sufficient distance out of the path of the holding faces of the teeth for a purpose which will be herein- 50 after more fully explained.

A tendency is constantly imparted to the 55 pawl or holder (as by gravity or spring pressure) to move said holder into the path of the teeth of the toothed member, so that said holder will be adapted to retain accumulative steps of said member during intermissions of the engagement of the train ac- 60 cumulated operating means therewith.

From the foregoing it is apparent that, 65 during each accumulative step of the toothed member, the holder or pawl is positioned to permit canceling or restoring movement of such member so that, while so positioned, such holder is ineffective to cause retention of accumulative movement previously im- 70 parted to said toothed member.

65 In accordance with still another feature of

this invention, a latch is provided for retaining the holding pawl in its ineffective position; said latch having a tendency imparted thereto (as by gravity or spring force) to move to a position in which it will retain 70 the holding pawl in its ineffective or permissive position. The relative construction of said latch and the holding pawl associated therewith is such that, when said holder is effectively positioned with relation to the toothed member associated therewith, said latch will be held thereby out of the path of the movement of said holder, and so that when said holder is moved to its ineffective or permissive position during any step of the accumulative movement thereof, such movement of said holder will cause it to permit said latch to act to retain such movement of said holder, to the end that said latch may 75 serve at certain times, for a purpose which will be hereinafter more fully described, to continue the ineffectiveness of said holder by preventing it from retaining previous accumulation and thereby permitting the toothed member to be restored to its normal 80 position.

The relative construction of the toothed member and the latch is such that, when said member is in its fully restored position, said latch will be held by said member out of the path of the holder associated therewith; and so that said latch will serve to stop said toothed member in its fully restored position, when said member has moved to cancel 95 previous accumulative movement thereof. 100

The accumulation mechanism (which comprises the toothed member, holder and latch just described), co-operates with the starting and stopping mechanism hereinbefore referred to, to the end that the effectiveness 105 of said accumulation mechanism, as to the retention of any successive accumulative movements imparted thereto by the signaling train, will be dependent upon the continuity of the running of the signaling train, after the conclusion of any operating cycle 110 thereof, as determined by the starting and stopping mechanism associated therewith.

The cooperation between the accumulation mechanism and the starting and stopping mechanism, as just referred to, is accomplished by suitable construction and arrangement with relation to a member forming part of the starting and stopping mechanism, which member occupies one or another of 115 several positions, dependent upon such mechanism being conditioned for starting or stopping the train controlled thereby. Such member will hereinafter be referred to 120 as a "determining member". 125

In detail, this feature of this invention is carried out by employing a determining member so formed that a part thereof will be disposed in the path of the latch associated therewith when said member is in the 130

position which it assumes when the starting and stopping mechanism is conditioned to cause or permit continued operation of the train governed thereby; and the relative construction of such determining member and latch, and of the toothed-member-holder associated therewith, is such that the retaining action of said latch will be prevented when the co-engaging part of such determining member is disposed in the path of said latch.

In applying this feature to signaling trains having a guide for the determining member, as hereinbefore more fully described, such determining member is adapted to occupy any one of three principal positions, two of which permit running of the train and the other of which causes stopping thereof. Suitable extraneous means are provided for moving such member to one of the said positions to start or permit continued running of the train; means is provided constantly tending to move such member to the stopping position thereof; and the associated guide serves, during operating cycles of the signaling train, to arrest the stopping movement of such member intermediate the starting and stopping positions thereof.

The arrangement of such determining member with relation to the latch associated therewith is such as to permit movement of said latch to the retaining position thereof only when said member is in its starting position.

In order to avoid impairing the responsiveness of such a determining member to the actuating forces provided therefor, the relative formation of the cooperating parts thereof is such that when the holding means is positioned to retain accumulative movement of the toothed member associated therewith, the latch will be held out of the path of the determining member; and so that when the holding member is ineffectively positioned, so as to permit restoring movement of the toothed member (and is therefore in position to be engaged by said latch for the purpose of being held in such ineffective position) said latch will be permitted to move into engagement with or into the path of said determining member.

Although the cooperative relation of an accumulation mechanism latch member and a starting-and-stopping-mechanism-determining member have been hereinbefore particularly described, it should be understood that this feature is also suited for use in signaling mechanism having a determining member which does not form part of starting and stopping mechanism, but which governs the retention and the cancelation or restoration of accumulative movement of step by step accumulation mechanism; and that the use of a latch, holder and toothed accumulation member constructed and arranged in accordance with this invention, is

particularly advantageous when the action or effectiveness of such a holder should be governed by a determining member operable by an agency of comparatively slight force.

In order to prevent loss of accumulative movement of the toothed member when the train is brought to rest after any given number of the operating cycles thereof; the tooth of said member, the lifting face of which is brought into engagement with the holding pawl during the accumulative step incident to the final one of such cycles is of insufficient height to raise said pawl enough to permit the latch to act to retain same in position to permit canceling or restoring movement of said toothed member.

This invention will be more fully understood by referring to the annexed drawings, throughout which like characters denote similar parts, and in which:

Figure 1 is a top or plan view of an electromagnetically controlled signaling device embodying the general and certain specific features of this invention;

Fig. 2 is a front elevation of the same;

Figs. 3 and 4 are, respectively, left-hand and right-hand end elevations of the same;

Fig. 5 is a front elevation of the interior mechanism of the device of Fig. 1; the front plate being removed, ends of shafts and similar parts being shown in cross section, and a portion of the main spring and the guide disc therefor being cut away to more clearly disclose the ratchet mechanism;

Figs. 6, 7, 8 and 9 are details to be referred to;

Fig. 10 is a diagrammatic representation of typical circuit connections provided for the code signaling contacts shown in Figs. 1, 2, 3, 4, 12, 13 and 14;

Fig. 11 is an illustrative diagrammatic representation of typical circuit connections and controlling contacts for the actuating magnet of the device of Figs. 1 to 5 inclusive;

Fig. 12 is a front elevation of a single-acting diaphragm-controlled signaling device embodying the general and certain other specific features of this invention;

Fig. 13 is a front elevation of a double-acting diaphragm-controlled signaling device embodying the general and certain further specific features of this invention;

Figs. 14 and 15 are, respectively, left-hand and right-hand end elevations of portions of the device of Fig. 13.

In the interest of clearness, parts fully shown on one or more views are omitted from other views, where if shown, they would so nearly obstruct or be obstructed by other parts as to render inclusion therein confusing.

The signaling device shown by Figs. 1 to 5 inclusive, comprises signaling train frame

plates 31 and 32, held in suitable spaced relation by the frame posts 33, 34 and 35 and by the magnet supporting brackets 36 and 37; and form a support for the various other parts of said device, as will be hereinafter more fully explained.

A suitable signaling train is supported between the plates 31 and 32, and comprises mechanism as follows: The main-spring 38, 10 one end of which is secured to the post 33 and the other end of which is secured to the main-shaft 39; the main gear 40 is carried by the shaft 39, and is driven by said shaft acting through the ratchet wheel 41 and dog 42; an intermediate gear 43 carried by the shaft 44 is driven by the main-gear 40 acting through the pinion 45; the code-wheel shaft 46 carries the gear 47 and is driven by the gear 43 acting through the pinion 48; 20 the escape-wheel 49 is carried by the shaft 50 and is driven by the gear 47 acting through the pinion 51; the escapement pallet 52 is carried by the shaft 53 and is operated by the wheel 49. The forward end of 25 the main-shaft 39 projects beyond the front face of the plate 32, said end being squared to facilitate engagement thereof by a suitable winding key. The rear end of said shaft 39 projects beyond the rear face of 30 the plate 31 and carries the pinion 54. The spring stop gear 55 is carried by the shaft 56 and engages the pinion 54, a tooth 57 (see Fig. 5) being so formed as to arrest the rotation of said pinion when engaged thereby. 35 Said gear 55 is so set with relation to the pinion 54 as to prevent overwinding of the main-spring 38.

A guard disc 58 is carried by the main shaft 39, for holding the main-spring 38 40 away from the ratchet dog 42. The shaft 46 projects beyond the front face of the plate 32, so as to be suited to carry a code-wheel for desired engagement with such circuit controlling contacts as may be mounted 45 upon the front side of said plate. The pallet shaft 53 carries thereon a pendulum 59 or other retarding mechanism of any well-known form, for suitably regulating the speed of rotation of the code-wheel 50 shaft 46.

Starting and stopping mechanism is provided for the signaling train just described; said mechanism comprising a determining lever 60, pivoted at 61 and having projections 62, 63 and 64; and a detent arm 66 is so carried by the pallet shaft 53 as to be caused to travel backwards and forwards across the path of the projection 62 during the actuation of said pallet by the escape-wheel 49.

Holding means is provided for the starting and stopping mechanism, comprising the guide disc 65, which is mounted in the path of the projection 64. Said disc is of 65 such diameter that, when the projection 64

is resting on the periphery thereof, the lever 60 will be supported in such position that the projection 62 carried thereby will be above the path of the arm 66, but the armature 67 will be such distance from the ends 70 of the cores of the magnet 68 as to permit further attractive movement thereof, for a reason which will be hereinafter more fully explained. A notch 69 is formed in the periphery of the disc 65 for receiving the 75 end of the projection 64, said notch being of such depth that, when the end of said projection 64 rests therein, the lever 60 will be in such position as to bring the projection 62 into the path of the arm 66, and thereby 80 arrest the running of the train.

Code signal formulating mechanism is provided, which mechanism comprises the code wheel 70 (see Fig. 2) carried by the shaft 46 of the signaling train, the trailing 85 contact 71 operable by said wheel, and the contacts 72 and 73 which co-engage with said contact 71. The contact 71 has an insulating end 74 secured thereto, said end being disposed in the path of the teeth of the code 90 wheel 70, to be moved thereby so as to bring the said contact 71 into engagement with the contacts 72 and 73, said contact 71 being so adjusted as to constantly tend to move away from said contacts 72 and 73. 95

The code wheel 70 is secured to the shaft 46 in such relation to the guide disc 65 carried thereby that the tooth 75 will be positioned to hold the contact 71 in engagement with the contacts 72 and 73 whenever the 100 notch 69 in said disc 65 is positioned to receive the projection 64.

The outline of the wheel 70 is arranged to provide teeth for the formulation of a code signal characteristic of some signal station location, being shown as arranged for the formulation of the code signal (....). It is evident that the formulation of the code signal represented by the outline of the code wheel 70 is controlled by the starting and stopping mechanism already described, and that such formulation will be accomplished a greater or lesser number of times as determined by the action of the said starting and stopping mechanism when the notch 69 115 is presented to the projection 64 after each formulating cycle of the train.

The electromagnet 68 and the armature 67 co-operating therewith constitute translating means for applying the energy of a suitable current source to the actuation of the starting and stopping mechanism; said armature being secured to the lever 60, and said magnet being carried by the brackets 36 and 37 in such position, with relation to said armature, that the effective energization of said magnet will cause said armature to swing the lever 60 so as to carry the projection 64 out of the notch 69 and a suitable distance above the periphery of the disc 65, 125

thereby carrying the projection 62 out of the path of the arm 66 and lifting the projection 63 to a position higher than that which it occupies when the projection 64 rests upon 5 the periphery of the disc 65.

A retractile spring 76 is so applied to the lever 60 as to tend to swing said lever so as to carry the projection 62 into the path of the arm 66, and to move the armature 67 10 away from the magnet 68. A toothed segmental member 77 is fixed upon the shaft 78, and said shaft is so located, with relation to the pin 79 carried by the disc 65, that said pin may engage the teeth of said member to impart counter-clockwise movement thereto. A spring 80 is secured to the shaft 78 and imparts a tendency thereto for clockwise movement.

A holding pawl 81 is secured to the shaft 20 82 in such relation to the member 77 that the bent over end 83 thereof may engage the teeth of said member to hold same against clockwise movement.

The pawl 81 is so positioned, with relation to the arc of movement of the pin 79, that, when the end 83 is engaged by a tooth of the member 77, the distance from the holding face of said pawl to said arc of movement will be somewhat less than the 30 distance between the holding faces of adjacent teeth of said member 77; to the end that said pin 79 may properly engage a tooth thereof when said member is held against clockwise movement by said pawl.

35 The member 77 is so formed and mounted in such relation to the arc of movement of the pin 79 that each revolution of the disc 65 will cause rotation of said member an angular distance somewhat in excess of that 40 between the holding faces of adjacent teeth of said member.

As most clearly shown by the enlarged view of Fig. 8; full sized teeth of the member 77 have a holding face 84 for engagement by the holding face 85 of the end 83, and a lifting face 86 for engagement by the lifting face 87 of said pawl; and that the junctions of such lifting and holding faces, of both such teeth and said pawl, are so 50 formed as to provide the bevels 88 and 89, respectively, which bevels act as lifting faces to raise said pawl during accumulation-cancelling or restoring movement of the member 77 for a reason which will be hereinafter 55 more fully explained.

The spring 90 (see Fig. 4) is so applied to the pawl 81 as to impart thereto a tendency to so swing as to bring the end 83 into the path of the teeth of the member 77.

60 The latch 91 is mounted upon the shaft 78 for rotation independently thereof; and the free end of said latch is disposed adjacent to the projection 63 carried by the lever 60. The spring 92 (see Fig. 4) is so applied to

the latch 91 as to impart a tendency to swing 65 the end thereof toward the projection 63.

The lug 93 is formed on one edge of the latch arm 91 for cooperation with the projection 94 carried by the pawl 81; and said parts are so relatively positioned that, when 70 the holding face of the end 83 of the pawl 81 is disposed in the path of the holding faces of the teeth of the member 77 (see Fig. 9), the projection 94 will be in the path of the lug 93; and so that when the pawl 81 is 75 raised so that the holding face of the end 83 thereof is out of the path of the holding faces of the full height teeth of the member 77 (see Figs. 6 and 7), the projection 94 will be raised high enough to permit ledge 80 93 to pass thereunder.

The pawl 81 is so mounted with relation to the lug 93 that the downward movement of the projection 94 along the vertical face of said lug 93 will tend to swing the free 85 end of the latch 91 away from the projection 63.

The pin 95 is carried by the member 77 and is so positioned thereon as to be adapted 90 to engage the latch arm 91, during clockwise movement of said member, to swing said latch away from the projections 63 and 94 and into engagement with the shaft 82. Said pin 95 is so positioned with relation to the teeth of the member 77 that, when said 95 member has turned clockwise on its shaft until its movement is arrested when said pin has moved said latch arm into engagement with the shaft 82, the extreme left-hand radial tooth face of said member will be disposed in the path of the pin 79 for effective operation thereby. The pin 95 therefore serves both for limiting the extent of the clockwise movement of the member 77 and as a means for disengaging the lug 93 from 105 the projection 94 when said member is in its fully restored position.

From the foregoing it will be seen that the member 77, the pawl 81 and the latch arm 91 serve as step-by-step mechanism intermittently engaged by the train operated pin 79, during the running of the train, for accumulative actuation therefor.

The latch arm 91 has a heel 96 formed thereon adjacent to the projection 63. Said heel and said projection being so relatively formed and arranged that, when the lever 60 is positioned to bring the armature 67 into engagement with the poles of the magnet 68, said projection 63 will be disposed 120 in the path of the heel 96, and will thereby prevent movement of the latch arm 91 in response to the spring 92 such as would carry the lug 93 into the path of the projection 94; and so that, when the lever 60 is 125 so positioned that the projection 64 rests upon the periphery of the disc 65, the projection 63 will be disposed below the path

of the heel 96, and will therefore permit such movement of the latch arm 91 in response to the spring 92 as will carry the lug 93 into the path of the projection 94.

5 From the foregoing it will be seen that the arrangement of the determining lever 60 with relation to the latch arm 91 is such as to prevent movement of said latch arm to effect supporting engagement between the 10 lug 93 and the projection 94 only when said lever is positioned to permit starting of the train upon complete attractive movement of the armature 67.

Because of the comparatively slight force 15 applied by the magnet 68 for the actuation of the armature 67, it is very desirable to avoid the application of needless frictional load to the determining lever 60 at any time when an operative determination is dependent upon movement of said lever, either in 20 response to the attractive effort of said armature, or to the retractive effort of the spring 76. To this end the relative formation of the cooperating parts of the lug 93 25 and the projection 94 is such that when the pawl 81 is positioned to retain accumulative movement of the toothed member 77, the latch arm 91 will be so positioned as to hold the heel 96 out of the path of the projection 68; and so that, when the pawl 81 is raised 30 to its ineffective position, said latch arm will be permitted to so move as to carry the lug 93 into the path of the projection 94.

In order to prevent accumulation-canceling or restoring movement of the member 77, as a result of deenergization of the magnet 68 during certain accumulative steps of 35 said member, the end of tooth 97 is cut off, and no lifting face is provided between the holding face 98 and the holding face of the tooth adjacent thereto. As a result of this 40 construction, the train may be brought to rest at the conclusion of the accumulative steps incident to the cycles of the operation 45 of said train during which either the tooth 97 or tooth 98 is moved past the end 83 of the pawl 81, as said teeth 97 and 98 are of insufficient height to raise said pawl enough 50 to permit the latch arm to act to retain same in position to permit canceling or restoring movement of the member 77.

The insulating cam 99 is fixed upon the shaft 78 so as to move with the member 77; and the contacts 100, 102, 103 and 110 are 55 mounted in suitable relation to said cam for operation thereby (see Figs. 10 and 11).

The free end of the contact 110 (best shown in Fig. 10) is disposed in the path of the rise 116 of the cam 99 at such distance 60 from the normal position thereof that rotation of said cam from its normal position, in a counter-clockwise direction, for an angular distance corresponding to that of three teeth of the member 77, will bring 65 said rise into engagement with said contact.

The depression 109 is formed in the cam 99 in the path of the free end of the contact 110, and said depression is so positioned as to be presented to the end of said contact when the cam 99 is rotated from its normal 70 position, in a counter-clockwise direction, for an angular distance corresponding to that of six teeth of the member 77. The contact 110 is connected to the contact 113 by the insulating spacer 112; said contacts 75 110 and 113 being normally spaced away from the contacts 111 and 114, respectively, and at such distance therefrom that, when the free end of said contact 110 is engaged by rise 116, said contact 110 will be brought 80 into engagement with the contact 111 and said contact 113 will be brought into engagement with the contact 114.

The contact 102 (as best shown in Fig. 11) normally rests against the contact 101 85 and is supported thereby in such position that the free end of said contact 102 is spaced from the portion of the cam 99 normally presented thereto so as to permit the rise 108 to freely pass thereunder. The 90 contact 100 is normally spaced away from the contact 101, and the free end of said contact 100 rests upon the cam 99 in the path of the rise 108, so that, when said cam 99 is rotated counter-clockwise an angular distance 95 corresponding to that of four teeth of the member 77, said rise will engage said contact 100 and move same into engagement with the contact 101.

The free end of the contact 102 is disposed 100 in the path of the rise 115 of the cam 99, and said free end is so positioned as to be engaged by said rise, to move said contact 102 away from the contact 101, when the cam 99 is rotated from its normal position 105 in a counter-clockwise direction for an angular distance corresponding to that of six teeth of the member 77.

The free end of the contact 103 is disposed 110 in the path of the rise 115 of the cam 99 at such distance from the normal position of said rise as to be engaged thereby, upon rotation of said cam 99 from its normal position, in counter-clockwise direction, for an angular distance corresponding to 115 that of two of the teeth of the member 77. Said contact 103 normally rests against the contact 104 and carries a spacer 106 for moving the contact 105. The contact 105 is normally spaced away from the contact 107 but may be moved into engagement therewith by the spacer 106; said parts being so relatively arranged that, when the free end of the contact 103 is moved away 120 from the cam 99 by the rise 115 thereof, said contact will be moved away from the contact 104, and will carry the spacer 106 to such position as to bring the contact 105 into engagement with the contact 107.

A typical arrangement of electrical con- 130

nections is diagrammatically illustrated by Figs. 10 and 11. In Fig. 10,—the conductors 140 and 141 represent line wires of a suitable signaling circuit; said conductor 5 140 being connected directly to the contact 72 and being connected through the conductor 143 with the contact 110; and said conductor 141 being connected through the conductor 144 with the contact 121, and being 10 connected through the conductor 145 with the contact 73.

The contact 117 has an insulating end 118 secured to the free end thereof for engaging the code signal formulating sector 15 146, the contact 119 being mounted below the contact 117 and the contacts 120 and 121 being mounted above said contact 117; and said parts being arranged for cooperation 20 in a manner and for a purpose which will be hereinafter more fully explained.

The contact 120 is connected through the conductor 147 with the contact 111. The contact 117 is connected through conductors 25 148 and 149 with contact 71, said contact 117 being also connected through said conductor 148 and through conductor 150 with contact 113. Contact 119 is connected through conductor 151 with contact 114; and said contact 114 has a ground connection 30 G applied thereto.

From the foregoing it will be seen that, under normal conditions, a current path is maintained, through the contacts as shown, between line conductor 140 and line conductor 141,—the ground connection G being disconnected therefrom. The current path between conductors 140 and 141 is normally maintained through contacts 72, 71 and 73 35 and conductor 145. The current path from the ground G is normally interrupted between contacts 114 and 113, and between contacts 119 and 117.

In Fig. 11, the battery 122 represents a local current source for the energization of 45 the magnet 68, and the signaling keys 123 and 124 are intended as diagrammatic representations of circuit closing means for independent current paths from said source to said magnet; and it should be understood 50 that such circuit closing means may be operable either manually or electromagnetically in response to circuits connecting any desired thermostatic or other devices, as service conditions may render most expedient. 55 One terminal of the battery 122 is connected through conductors 125 and 126 with one member of the keys 123 and 124. The other member of key 123 is connected through conductors 127 and 128 to contact 104 and 60 through conductors 127 and 129 to contact 101. The other member of key 124 is connected through conductors 130 and 131 with contacts 103 and 105. The conductor 132 connects conductor 125 with contact 107, and

the conductor 133 connects said conductor 65 132 with the contact 100.

The other terminal of the battery 122 is connected through conductors 134 and 135 with one end of the winding of electromagnet 68, the other terminal of said winding 70 is connected through the conductor 136 with contact 102.

The local alarm bell 137 is provided for a purpose which will be hereinafter more fully explained; one terminal of said bell 75 being connected through the conductor 138 to conductor 134, and the other terminal of said bell being connected through the conductor 139 to the conductor 131.

From the foregoing it will be seen that 80 the controlling means of which the insulating cam and cooperating contacts, shown in Fig. 11 forms part, is arranged to so govern the function of the starting and stopping mechanism responsive to the magnet 68 85 that, after predetermined action of the train, said mechanism will act to stop the running thereof, regardless of the actuation of the keys controlling the force of the battery 122. For example; when the rotation 90 of the cam 99 for an angular distance corresponding with that of two teeth of the member 77, brings the rise 115 into engagement with the free end of the contact 103, as hereinbefore more fully explained, the 95 movement of said contact away from the contact 104, incident to such engagement will render the electromagnet 68 unresponsive to such actuation of the key 124 as is intended to apply the force of the battery 100 122 thereto through the current path controlled by said key. For further example; when the rotation of the cam 99, for an angular distance corresponding with that of six teeth of the member 77, brings the rise 105 115 into engagement with the free end of the contact 102, as hereinbefore more fully explained, the movement of said contact away from the contact 101 will render the electromagnet 68 unresponsive to the actuation 110 of the keys 123 and 124.

It will further be seen that the magnet 68 is normally deenergized, that the alarm bell 137 is normally silent, and that there is no current flow from the battery 122 other 115 than when one of the abnormal current paths are established as, by the closure of the contacts of the signal keys 123 and 124, or while contacts 100 and 102 both engage contact 101.

The sector 146 is secured to the shaft 46 in such position, with relation to the code wheel 70, that the portions of said sector which are of greatest radius will be presented to the end 118 of the contact 117 when 125 said code wheel is so positioned with relation to the end 74 of the contact 71 that none of the teeth of said code wheel will

engage with said end. Said sector is further so positioned upon said shaft with relation to the notch 69 formed in the disc 65 that said sector will support the contact 117 intermediate the contacts 119 and 120 whenever said notch is positioned to receive the projection 64, and so that when said disc 65 is rotated clockwise from the normal position thereof so as to withdraw the notch 69 from the path of the projection 64, said sector will be withdrawn from the path of the end 118 carried by the contact 117, and so that said sector will re-engage said end 118 only after further clockwise rotation thereof for an angular distance greater than that occupied by the code teeth of the wheel 70.

The lever 152 is fixed upon the shaft 153 and carries the extension 154 for engaging the shaft 56, and an insulating pin 155 is secured to the free end of the lever 152 and is arranged for engagement with the free end of contact 105 as best shown in Fig. 11.

A portion of the shaft 56 is cut away, as indicated by Fig. 5, so that, when the main spring 38 is fully wound, such cutaway portion will be presented to the free end of the extension 154 and thus permit the lever 152 to swing upwardly in response to the pressure of contact 105 against the insulating pin 155; and so that the rotation of the shaft 56 incident to the unwinding of said main spring to a predetermined point will sufficiently withdraw such cutaway portion from the free end of the extension 154 as to cause said extension to so swing the lever 152 as to cause the pin 155 to move the contact 105 into engagement with the contact 107.

Manually operable means is provided for withdrawing the pawl 81 from the path of the teeth of the member 77; said means comprising the pull rod 156 which is supported in the guides 157 and 158, the upper end of said rod being bent over and coiled around said rod below the guide 157 so as to form an abutment 159 for one end of the spring 160. The compression spring 160 is coiled around the rod 156 between the abutment 159 and the guide 158. The handle 161 is hinged to the lower end of the pull rod 156, and the extension spring 162 connects the upper end of said pull rod with the pawl 81. The various parts of said manually operable means are so constructed and arranged that, under normal conditions, the spring 160 will support the rod 156 in its fully elevated position, thereby fully releasing the tension of the spring 162; and so that, when the member 77 is being held against clockwise rotation by the engagement of the end of the pawl 81 therewith, if the handle 161 is moved downwardly, the spring 162 will be extended until the tension thereof is sufficient to overcome the

frictional load between the end 83 of the pawl 81 and the tooth of the member 77 in engagement therewith, besides overcoming the tension of the spring 90 acting to hold said pawl in engagement with said member, whereupon, said pawl 81 will be quickly withdrawn from the path of the teeth of the member 77, and will be held out of the path of such teeth until said handle 161 has been permitted to move upwardly far enough to enable the spring 90 to swing the pawl 81 into the path of the teeth of the member 77.

The operation of the signaling device shown by Figs. 1 to 11 inclusive, is as follows:

Assuming that the main spring 38 is fully wound, the magnet 68 is deenergized, the projection 62 is disposed in the path of the arm 66, the member 77 is in its fully restored condition, and electrical connections are provided as shown in Figs. 10 and 11 (the various parts being disposed as shown in Figs. 1, 2, 3, 4, 5, 10 and 11); should the contacts of key 124 be closed for a comparatively short period, the alarm bell 137 will sound while said contacts are closed, and the train will act for one operative cycle thereof, and the various parts of said train will thereupon be restored to their respective normal positions. Such sounding of the alarm bell 137 in response to such closure of the contacts of key 124 results from the establishment of a current path as follows: from one terminal of battery 122, through conductors 125 and 126 to one contact of said key 124, from the other contact of said key, through conductors 130 and 139 to one terminal of the alarm bell 137; from one terminal of said alarm bell through conductors 138 and 134 to the other terminal of battery 122.

The starting of the signaling train in response to the closure of the contacts of the key 124 as just described, resulted from current flow through the following paths:—from one terminal of battery 122, through conductors 125 and 126 to one contact of key 124; from the other contact of said key, through conductors 130 and 131 to contact 103, thence through contact 104 and conductors 128 and 129 to contact 101; thence through contact 102 and conductor 136 to one end of the winding of electromagnet 68, thence through said winding and through conductors 135 and 134 to the other terminal of said battery 122.

Upon energization of magnet 68, as just described, the armature 67 (see Fig. 5) is attracted thereby, swinging the determining lever 60 so as to withdraw the projection 62 from the path of the arm 66 thereby permitting the signaling train to start. When the signaling train is thus started, the notch 69 is quickly moved out of the path of the

projection 64, whereupon the disc 65 provides a support for the projection 64, whereby the lever 60 will be held against such movement as would carry the projection 62 into the path of the arm 66; thus assuring continued operation of the train until the completion of one operative cycle thereof, even though the magnet 68 becomes deenergized after a comparatively brief period, due to the separation of the contacts of the key 124.

When the notch 69 has been moved out of the path of the projection 64, as just described, and the sector 146 on the shaft carrying discs 65 has been withdrawn from the path of the end 118, the contact 117 will move into engagement with the contact 119, thus establishing a connection between the ground G and the line conductors 140 and 141; said connection being established through the conductor 151, the contacts 119 and 117, and the conductors 148 and 149, to the contact 71 which forms a part of the current path between said conductors 140 and 141.

After the ground G has been connected with the line conductors 140 and 141, as just described, the further rotation of the code wheel 70 for an angular distance corresponding to that throughout which other teeth of said wheel serve to hold the contact 71, by means of insulating member 74, against the contacts 72 and 73, will withdraw the tooth 75 from the path of the contact 71, and said contact will thereupon move away from the contacts 72 and 73, thus interrupting the current path between conductors 140 and 141 and disconnecting the ground G from both of said conductors. During still further rotation of the code wheel 70, the other teeth thereof will successively engage and disengage the end 74, and thereby alternately move the contact 71 into engagement with the contacts 72 and 73, and then permit said contact 71 to move away therefrom, so as to complete the formulation of the code signal for which the outline of said code wheel is arranged. It is evident that each time the contact 71 is thus brought into engagement with the contacts 72 and 73 a current path will be established between the conductors 140 and 141, and the ground G will be connected thereto; and that each time said contacts are separated said path and said connection will be interrupted.

After the last one of the teeth of the code wheel 70 has disengaged the end 74, as just described, the sector 146 will engage the end 118 and thereby move the contact 117 away from the contact 119 and into engagement with the contacts 120 and 121. Such movement of said contact 117 will not, however, establish a current path between the conductors 140 and 141 nor connect the ground G thereto because the current path from

the contact 120 through the conductor 147 is open at the contact 111, and the current path from the contact 117 through the conductor 148 is broken at the contact 71 and at the contact 113.

During the further running of the train, after both of the higher raised surfaces of the sector 146 have disengaged the end 118, said end will rest upon the intermediate surface of said sector thereby holding the contact 117 away from the contact 119, while permitting said contact 117 to move away from the contacts 120 and 121; and the pin 79 will be carried by the disc 65 into engagement with a tooth of the member 77 and will thereby swing said member in a counter-clockwise direction an angular distance somewhat in excess of that between the holding faces of adjacent teeth thereof. Such movement of the member 77 will act, through the shaft 78, to correspondingly move the cam 99, (see Fig. 2) but such movement of said cam will be insufficient to cause any of the rises formed thereon to engage contacts which are arranged for cooperation therewith.

The movement of the member 77, as just described, will withdraw the pin 95 from engagement with the latch arm 91, and will, at the same time raise the end 83 of the pawl 81 so as to carry the projection 94 above the path of the lug 93. Inasmuch as the deenergization of the magnet 68 had previously permitted the projection 64 to move into engagement with the disc 65, the projection 63 will now be disposed below the path of the heel 96, and the arm 91 will therefore be permitted to move in response to the spring 92 so as to carry the lug 93 into the path of the projection 94, as shown in Fig. 7, thus preventing the pawl 81 from swinging in response to the spring 90 so as to move the holding face of the end 83 of said pawl into the path of the holding faces of the teeth of the member 77. Thereafter, and just prior to the point in the running of said train when the notch 69 is again presented to the projection 64, the pin 79 will be moved out of the path of the teeth of the member 77, and thereupon said member will be moved clockwise by the spring 80 to the position shown in Fig. 5.

After the controlling mechanism parts have been permitted to return to their respective normal positions, as just described, the tooth 75 of the code wheel 70 will engage the end 74 and thereby move the contact 71 against the contacts 72 and 73, thus reestablishing a current path between the conductors 140 and 141, but without connecting the ground G therewith, because the ground connection previously effective is now broken between the contacts 119 and 117.

After the contacts have been restored to their normal condition, as just described, the

notch 69 will be presented to the projection 64, and the determining lever 60 will thereupon move in response to the spring 76, so as to carry the projection 62 into the path of 5 the arm 66, and thus bring the signaling train again to rest.

Should the contacts of key 124 be closed for an extended period, instead of for a period of comparatively short duration, as just 10 described, the train will act for two operative cycles thereof, and will come to rest with the controlling mechanism thereof so conditioned as to render the magnet 68 unresponsive to closure of the key 124, the 15 alarm bell 137 being caused to ring continuously until the member 77 has been restored to its normal position. When running in response to a continued closure of the contacts of the key 124, such as just described, the 20 functioning of the various parts is the same as the response already described to a closure of said contacts which is of comparatively short duration, except for the fact that the lever 60 will be held in its fully elevated position because of the continued attraction of 25 the armature 67 by the magnet 68 until after the pin 79 has moved the member 77. Owing to the fact that the lever 60 is maintained in its fully elevated position, the projection 63 30 carried thereby will be disposed in the path of the heel 96 of the latch arm 91, when the pawl 81 is elevated by a tooth of the member 77 so as to carry the projection 94 above the path of the lug 93, as shown in Fig. 6. 35 While the latch arm 91 is thus held by the projection 63, the holding face 83 of the end of the pawl 81 will move into the path of the holding face of the tooth of the member 77 which had just previously raised said 40 pawl, and the operating cycle of the signaling mechanism will thereupon be repeated; and, incidentally thereto, the rise 115 of the cam 99 will move the contact 103 away from the contact 104, and such movement will be 45 transmitted through the spacer 106 to move the contact 105 into engagement with the contact 107.

At the conclusion of the second operating cycle, under the conditions just described, 50 the train will be brought to rest when the notch 69 is presented to the projection 64; and the accumulative movement of the member 77 will be retained, inasmuch as the tooth 97 of said member will not raise the 55 pawl 81 high enough to permit the lug 93 to move into the path of the projection 94. The movement of the contact 103 away from the contact 104, as just described, will interrupt the current path through the magnet 68 which was established by the closure of the 60 contacts of the key 124, thus causing deenergization of said magnet and permitting the lever 60 to move in response to the spring 76 so as to bring the train to rest.

65 When the train has been brought to rest,

as just described, it is evident that the electromagnet 68 will be unresponsive to the actuation of the key 124, but that said train will remain responsive to closures of the contacts of the key 123. It is also evident that, 70 because of the closure of the contacts 105 and 107, a current path will be established from one terminal of the battery 122 through conductors 125 and 132 to contact 107, thence through contact 105 and conductors 131 and 75 139 to one terminal of the bell 137 and from the other terminal of said bell through conductors 138 and 134 to the other terminal of the battery 122. The bell 137 will thus be caused to sound throughout the time that the 80 train stands at rest after two operative cycles thereof under the conditions just described.

If the contacts of key 123 are closed when the train is at rest with the member 77, and cam 99 in the position assumed thereby after 85 two accumulative steps thereof, as just described, the magnet 68 will be energized and the train will operate for a greater or less number of the operative cycles thereof, dependent upon the duration of the closure of 90 the contacts of said key, as hereinbefore more fully described. Should the closure of the contacts of such key continue for a period of such brief duration that the magnet 68 will be deenergized during the first 95 operative cycle of said train in response thereto, the member 77 and parts moving therewith will be restored to normal position, as hereinbefore more fully described. Should the contacts of the key 124 be closed 100 at the time such parts are so restored to their normal position, the running of the train will continue for two additional operative cycles thereof, and the train will thereupon be brought to rest, as hereinbefore more fully 105 described.

When the signaling device is in normal condition, as hereinbefore more fully described, should the contacts of key 123 be closed for a comparatively brief period, the 110 result will be the same as that ensuing from a closure of the contacts of the key 124 for a corresponding duration; the current path established by closing the contacts of key 123 being from one terminal of the battery 115 122, through conductors 125 and 126 to one terminal of said key 123, from the other terminal of said key, through conductors 127 and 129 to contact 101 and the remainder of 120 the current path including the winding of the magnet 68, as hereinbefore described.

Should the contacts of key 123 be closed for an extended period, instead of for a period of comparatively brief duration, as just described, the train will act for six operative cycles thereof, and will come to rest with the controlling mechanism thereof so conditioned as to render the magnet 68 unresponsive to closures of either the key 123 125 or key 124; the alarm bell 137 being caused 130

to sound continuously until the member 77 has been manually restored to its normal position.

The operation of the train in response to a maintained closure of the contacts of the key 123, such as just described, during the first operative cycle thereof, will be the same as that previously described as occurring in response to a closure of the contacts of said key of comparatively short duration, except as to the determining lever 60 and the controlling mechanism. Owing to the continued closure of the contacts of said key 123, the lever 60 will be maintained in its fully elevated position, and the projection 63 carried thereby will be disposed in the path of the heel 96 of the latch arm 91 when the pawl 81 is so lifted by a tooth of the member 77 as to carry the projection 94 above the path of the lug 93 (see Fig. 6). Said projection 63 will therefore prevent such movement of the latch arm 91 as would carry the lug 93 into the path of the projection 94, and as soon as the holding face of the tooth 25 which had so raised the pawl 81 passes to the left of the holding face of the end 83 of said pawl, the spring 90 will cause said pawl to so move as to bring said end 83 into the path of the teeth of the member 77, and thus cause the projection 94 to so engage the vertical face of the lug 93 as to swing the latch arm 91 out of engagement with the projection 63, as shown in Fig. 9.

After one accumulative step of the controlling mechanism has been taken and retained, as just described, the subsequent running of the train will cause the notch 69 to be again presented to the projection 64, as was the case when the train was acting in response to a key closure of comparatively short duration, as previously described. Owing to the fact that the continued closure of the contacts of key 123 will now cause the magnet 68 to retain the armature 67 in fully attracted position, the running of the train will be continued for another operative cycle thereof corresponding with the cycle hereinbefore more fully described, except as to the functioning of the controlling mechanism and of the contacts operable thereby. It is evident that during such second operative cycle the pin 79 will engage the second tooth (from the left-hand end) of the member 77, and that the lifting face of the tooth 97 will not raise the pawl 81 high enough to carry the projection 94 out of the path of the lug 93; hence the accumulative step thus imparted to the member 77 will be retained regardless of whether the magnet 68 is energized when the tooth 97 is moved past the end 83 of the pawl 81. During such second accumulative step of the member 77, the rise 115 of the cam 99 will be brought into engagement with the contact 103, and will move said contact away from contact 104. The movement of the contact 103 by the rise 115, as just described, will be transmitted through the spacer 106 to the contact 105, to move same into engagement 70 with the contact 107.

After the second accumulative step of the controlling mechanism has been taken and retained, as just described, the ensuing operation of the train will cause the notch 69 to be again presented to the projection 64. Owing to the continued closure of the contacts of the key 123, the magnet 68 will remain energized, the armature 67 will be retained in its fully attracted position, and the running of the train will continue for another operative cycle thereof. During such third operative cycle, the pin 79 will engage the third tooth (from the left-hand end) of the member 77, and the lifting face of a tooth thereof will raise the pawl 81 high enough to carry the projection 94 out of the path of the lug 93; hence the retention of the accumulative step thus imparted to the member 77 is dependent upon the continuity of the energization of the magnet 68 throughout the period during which said pawl is so raised. During such third accumulative step of the member 77 the rise 116 will be brought into engagement with the contact 110, and will move said contact into engagement with the contact 111; such movement of said contact being likewise imparted, through the spacer 112, so as to move the contact 113 into engagement with the contact 114. After the third accumulative step of the controlling mechanism has been taken and retained, as just described, the notch 69 will be again presented to the projection 64, and the continued closure of the contacts of the key 123 will continue the energization of the magnet 68 and thereby retain the armature 67 in fully attracted position, thus permitting the train to run for a fourth operative cycle thereof. During such fourth cycle, after the last one of the teeth of the code wheel 70 has disengaged the end 74 of the contact 71; the movement of the contact 117 in response to the engagement of the end 118 thereof by the sector 146 will establish a current path between the conductors 140 and 141, and will connect the ground G thereto, because of the actuation of the contacts 110 and 113 during the third accumulative step of the cam 99. The current path so established extends from the conductor 140, through the conductor 143 to contact 110 thence through contact 111 and conductor 147 to contact 120, thence through contacts 117 and 121 and through conductor 144 to line conductor 141. The ground connection with said current path is established from the ground G through contacts 113 and 114, and through conductor 130.

tors 150 and 148 to contact 117; which contact forms part of the current path just described between line conductors 140 and 141.

5 From the foregoing it will be seen that a different signal will be formulated during the fourth and following operative cycles of the signaling train than that formulated during the first three cycles thereof, in that 10 both the code wheel 70 and the sector 146 will be effective successively and in alternation, so as to formulate the code signal . . . — — which consists of the code signal . . . with the suffix — —

15 After the complete formulation of said code signal, the rise 108 of the cam 99 will be moved, incident to the fourth accumulative step of the member 77, so as to bring the contact 100 into engagement 20 with the contact 101; a current path will thereupon be established, between the battery 122 and the magnet 68, from one terminal of said battery, through conductors 125, 132 and 133 to contact 100, thence 25 through contacts 101 and 102 and conductor 136 to one end of the winding of the electromagnet 68, and from the other end of the winding of said magnet, through conductors 135 and 134 to the other terminal 30 of said battery. It is evident that the establishment of said current path will assure running of the signal train for further operative cycles thereof regardless of the continued closure of the contacts of the 35 key 123.

During the ensuing operative cycles of 40 said signaling train, both the code wheel 70 and the sector 146 will act effectively in the formulation of their code signaling impulses and the various parts of said train and the 45 accumulation mechanism actuated thereby will function in a manner similar to that hereinbefore described.

45 During the sixth accumulative step of the member 77 the rise 115 of the cam 99 will be brought into engagement with the contact 102 and will thereby move said contact away from the contact 101; thus assuring deenergization of the electromagnet 68. Inasmuch as the tooth 98 of said member 77, 50 which engages the pawl 81 during the sixth accumulative step of said member, does not so raise said pawl as to carry the projection 94 above the lug 93; it is evident that such deenergization of the magnet 68 will not result in a cancellation or restoration of the accumulative movement of said member, but that the signaling train will be brought to 55 rest at the conclusion of the sixth operative cycle thereof.

Had the contacts of the key 123 been open during the first or third accumulative steps of the member 77, it is evident that the pawl 81 would have become latched in its elevated 60 position, as indicated by Fig. 7, and would

thereupon have permitted cancellation of such accumulative movement and restoration of the member 77 to its normal position.

From the foregoing it will be noted that the frictional load resulting from the engagement of the heel 96 with the projection 65 is effective but once during each operative cycle of the signaling train, and that only during the brief period while the pawl 81 is maintained in its fully elevated or ineffective position during the passage thereunder of a full height tooth of the member 77; with the possible addition of the time required for the restoration of said member to its normal position in the event of said pawl being retained in its elevated or ineffective position when the pin 79 is out of the path of the teeth of the member 77 and said member is not in its fully restored position.

If the operation of the train is continued 70 or repeated without the rewinding of the main spring 38, until said spring is unwound sufficiently to withdraw the cutaway portion of the shaft 56, from the path of the extension 154 carried by the lever 152, said 75 lever will be so moved by said shaft as to cause the insulating pin 155 to hold the contact 105 in engagement with the contact 107.

When the main spring has run down to a degree such as will result in the pin 155 holding the contact 105 in engagement with the contact 107, as just described, if the pawl 81 is disengaged from the member 77, and said member is thereupon restored to its 80 normal position, it is evident that the magnet 68 will be energized, and that the train will run for two operative cycles thereof, thus causing the formulation of the code signal for which the wheel 70 is arranged, 85 without the suffix which may be formulated by the sector 146, and that said train will thereupon come to rest. The current path through which said magnet will be energized under the conditions just described is 90 as follows, from one terminal of the battery 95 122, through conductors 125 and 132 to contact 107, thence through contacts 105, 103 and 104 and conductors 128 and 129 to contact 101, thence through contact 102 and conductor 136 to one end of the winding of 95 the magnet 68, and from the other end of said winding, through conductors 135 and 134 to the other terminal of said battery 122.

The signaling device shown by Fig. 12, 100 comprises a suitable signaling train, such as that shown in Fig. 5, has a starting and stopping mechanism, a determining lever 60 pivoted at 61 and having projections 62, 63 and 64; and a detent arm 66 carried by the 105 pallet shaft 53. The guide disc 65 has the 110 notch 69 formed therein and is arranged to co-operate with the projection 64 in a manner corresponding to that hereinbefore 115 described in connection with Fig. 5.

120 Code signal formulating mechanism is 125

provided, such as that best shown by Fig. 10, and is arranged for operation in response to the running of the signaling train, as hereinbefore more fully described.

5 A diaphragm 170 is secured to the chamber 171, which chamber is mounted in suitable relation to the signaling train. The actuating lever 172 is pivoted at 173 and is mounted in suitable relation to the diaphragm 170 for actuation thereby. A stud 174 is secured to the diaphragm 170, said stud having a recess 175 in the upper end thereof. One end of the bar 176 projects into the recess 175 and is arranged for movement freely therein; the other end of said bar is fulcrumed to the lever 172 by the pin 177. A coil spring 178 encloses the upperly projecting portion of the stud 174 and the lower portion of the bar 176, and an adjustable abutment 179 is secured to the bar 176, whereby the movement of the diaphragm 170 may be transmitted, through the spring 178, to said bar 176.

A projection 180 is carried by the free end of the lever 172, said projection being arranged to engage the frame post 34 for the purpose of suitably limiting the upward movement of said lever 172. A dog 181 is pivoted to the front side of the lever 172 at 182, and the spring 183 is coiled around a rearwardly extending end of the pivot 182, the end 184 of said spring being secured to the lever 172, and the other end of said spring being so formed as to be disposed around the left-hand vertical edge of the downwardly projecting end 185 carried by lever 172, said other spring end being secured to the dog 181 at 186. Said spring 183 tends to swing the dog 181 around the pivot 182 in a counterclockwise direction, such movement of said dog being limited by the engagement of the lower portion of said spring with the edge of the end 185 of the lever 172.

45 When the dog 181 is in its normal position, as shown, the upper end 187 thereof, is so positioned that the upward movement of the lever 172 will be imparted to the lever 60' by the engagement of said end 187 with the projection 63.

The segment 188 is secured to the shaft 78 and moves with the member 77, (shown in Figs. 6, 7 and 9) said segment being mounted in the path of the end 185 and has the arcuate faces 189 and 190 for co-operation therewith. The radius of the face 189 is such as to permit the lever 172 to swing downwardly far enough so that the end 187 of the dog 181 may freely pass under the projection 63 of the lever 60' when the projection 64 of said lever rests in the notch 69, and the radius of the face 190 is such that, when the end 185 is engaged thereby, the lever 172 will be so elevated that, if the end 187 is beneath the projection 63, the

projection 62 will be held out of the path of the arm 66 and the projection 63 will be disposed in the path of the heel 96 of the latch arm 91.

The faces 189 and 190 are so positioned with relation to the teeth of the member 77, that when said member has been moved from its normal position in a counterclockwise direction for an angular distance corresponding to that of three teeth of said member, the face 190 will support the end 185.

The lug 191 is carried by the segment 188 and projects forwardly therefrom; and said lug is so positioned with relation to the lower end of the dog 181 and to the teeth of the member 77 that, when the said member is rotated from the normal position thereof, in a counterclockwise direction for an angular distance corresponding with that of six of the teeth of said member, said lug 191 will engage the lower end of the dog 181, and will thereby swing the end 187 of said dog out of the path of the projection 63.

The operation of the embodiment of this invention, which is illustrated by Fig. 12, is as follows:—

Under normal conditions, the various parts occupy the respective positions shown. If, now, a suitable source of liquid or gaseous pressure is applied to the chamber 171, the diaphragm 170 will be moved upwardly, and such movement will be transmitted through the spring 178 and the bar 176 to the lever 172, thereby swinging the free end of said lever upwardly.

Such upward movement of the lever 172 will be transmitted through the dog 181 and the projection 63 to the determining lever 60', and will swing said lever so as to withdraw the projection 62 from the path of the detent arm 66 and thereby permit the train to run for a greater or lesser number of the operative cycles thereof, as determined by the duration of the period during which the lever 172 is maintained in elevated position. Should said lever be maintained in elevated position for but a comparatively brief period, the accumulation mechanism will be restored to its normal condition when the pin 79 is next carried out of the path of the member 77 (see Fig. 5) after the termination of said brief period and the train will thereafter be brought to rest when the notch 69 is presented to the projection 64.

Should the lever 172 be maintained in elevated position until the conclusion of three operative cycles of said train, the face 190 will be carried into the path of the end 185, and will thus support the arm 172 in its elevated position, throughout additional operative cycles of said train regardless of the subsequent action of the diaphragm 170.

When the face 190 has been carried into

the path of the end 185, as just described, the running of the train will be continued for an additional three operative cycles thereof; and, during the third of such 5 operative cycles, the lug 191 will engage the lower end of the dog 181, and will thereby swing the end 187 out of the path of the projection 63, so as to permit the lever 60' to carry the projection 62 into the path of 10 the arm 66 when the notch 69 is next presented to the projection 64 and thus arrest the running of the train.

Should an excessive pressure be applied to the diaphragm 170, the projection 180 15 will prevent overtravel of the lever 172 and parts moving therewith, and the spring 178 will prevent injury to said lever or to the portions of the signaling train engaged thereby.

20 The signaling device shown by Figs. 13, 14 and 15 comprises a suitable signaling train, such as that shown by Fig. 5, has a starting and stopping mechanism, a determining lever 60' pivoted at 61 and having 25 projections 62, 63 and 64; and a detent arm 66 carried by the pallet shaft 53. The guide disc 65 has the notch 69 formed therein and is arranged to co-operate with the projection 64 in a manner corresponding to that 30 hereinbefore described in connection with Fig. 5.

Code signal formulating mechanism is provided, such as best shown in Fig. 10, and is arranged for operation in response to the 35 running of the signaling train, as hereinbefore more fully described.

A diaphragm 170' is secured to the chamber 171', which chamber is mounted in suitable relation to the signaling train. A 40 bridge 192 is secured to the chamber 171' in spaced relation above the diaphragm 170', and an adjustable bushing 193 is secured to said bridge in such position as to provide an abutment for the spring 194 and a guide 45 for the bar 195. The lower end of the bar 195 is secured to the diaphragm 170', and said bar extends upwardly from said diaphragm through the spring 194 and the adjustable bushing 193. The upper end of 50 said bar 195 has the enlarged threaded portions 196 and 197, and carries a spacing block 198 intermediate said threaded portions. The flanges 199 and 200 are carried by the bar 195; the flange 199 being freely 55 slidable lengthwise upon said bar between the upper end of the threaded portion 196 and the lower face of the block 198; and the flange 200 being correspondingly slidable upon said bar between the lower end of the 60 threaded portion 197 and the upper face of the block 198. The flange 199 is normally held against the lower face of the block 198 by the spring 201, which spring is held under suitable compression by the nut 202 65 which engages the threaded portion 196 of

the bar 195. The flange 200 is correspondingly held against the upper face of the block 198 by the spring 203, which spring is similarly held under compression by the nut 204.

70 The actuating lever 172' is pivoted at 173' in suitable relation to the flange 199, so that the rearwardly projecting lug 205 carried by said lever 172' will be engaged by said flange 199, when the bar 195 is moved upwardly by the diaphragm 170'.

A projection 180 is carried by the free end of the lever 172' to engage the frame post 34, so as to suitably limit the upward movement of said lever; a dog 181' is pivoted upon the lever 172' at 182 and is provided with a spring 183 the upper end 187' of said dog being arranged to engage the projection 63; the lug 191 carried by the segment 188 is provided for the operation of said dog 181'; and the end 185 of the lever 172' engages the segment 188 for actuation thereby; all as hereinbefore more fully described in connection with similar parts 85 of Fig. 12.

90 The auxiliary lever 206 is pivoted on the shaft 207, said lever being disposed between the lever 172' and the rear plate 31. The forwardly projecting lug 208 is carried by the lever 206, said lug being disposed in the path of the flange 200, to be engaged thereby when the bar 195 is moved downwardly by the spring 194. The free end of the lever 206 is provided with a projection (not shown) similar to the projection 180 carried 100 by the lever 172'; as shown in Fig. 13. A dog 181 is secured to the free end of the lever 206 by means of a pivot 182 and has a spring 183 applied thereto, all of said parts being arranged in a manner similar to the 105 parts of corresponding numbers, carried by the arm of the lever 172' as hereinbefore more fully described.

An arm 209 is secured to the shaft 78, the free end of said arm being so positioned that, when the member 77 is rotated in a counterclockwise direction from the normal position thereof, for an angular distance corresponding with that of two of the teeth of said member, said arm 209 will engage the lower end of the dog 181', and will thereby swing the end 187' of said dog out of the path of the projection 63 carried by the determining lever 60'.

110 It will be noted that Fig. 14 is confined to a portrayal of the translating means for controlling the starting and stopping mechanism, the signaling train parts (with the exception of the shaft 46) being omitted in the interest of clearness. For like reasons, Fig. 15 is limited to a representation of parts carried by the shafts 61, 78, 82, 173', and 207, and only shows such other parts of the device as are deemed essential to a clear 115 understanding of the parts peculiar to this 120 125 130

type of mechanism; and the parts carried by the shaft 78 are shown in operated position (instead of the normal position as shown by Fig. 13) for the purpose of more clearly disclosing the operative relationships between the lug 191 and the lower end of the dog 181', and between the free end of the arm 209 and the lower end of the dog 182". The operation of the embodiment of this invention which is illustrated by Figs. 13, 14 and 15 is as follows:—

Under normal conditions, the various parts occupy the respective positions shown in Fig. 13; it being assumed that a suitable source of liquid or gaseous pressure is being applied to the chamber 171' so as to cause the diaphragm 170' to force the bar 195 upwardly, against the tension of the spring 194, to such position that the flanges 199 and 200 will be free from the lugs 205 and 208, respectively. If, under these conditions, the pressure applied to the diaphragm 170' is substantially decreased, the spring 194 will move the bar 195 downwardly, and will thus cause the flange 200 to engage the lug 208 and to thereby swing the free end of the lever 206 upwardly. Such upward movement of the lever 206 will be transmitted, through the dog 181" carried by said lever, to the projection 63 of the determining lever 60'; and will thus serve to move said lever to disengage the projection 62 from the detent arm 66 and to thereby permit the signaling train to run. If the lever 206 is thus maintained in elevated position for but a comparatively brief period,—the train will be brought to rest when the notch 69 is next presented to the projection 64 after the code wheel shaft 46 has revolved once; and the parts moving with the shaft 78 will be restored to their normal position, as hereinbefore more fully described. Should the lever 206 be maintained in elevated position for an extended period, the code wheel shaft 46 will revolve twice, thus imparting two accumulative steps to the shaft 78 and the parts moving therewith.

During the second of such accumulative steps,—the free end of the arm 209 will engage the lower end of the dog 181", and will thereby swing the end 187" of said dog out of the path of the projection 63; thus permitting the lever 60' to swing the projection 62 into the path of the detent arm 66 when the notch 69 is presented to the projection 64. Inasmuch as the tooth 97 of the member 77 would not raise the pawl 81 high enough to permit the lug 93 to pass under the projection 94; (for the reason hereinbefore more fully described) it is evident that the two accumulative steps thus imparted to the member 77 and parts moving therewith will be retained; that the sig-

naling train will come to rest after two 65 operating cycles thereof; that after so coming to rest said train will be unresponsive to the downward movement of the bar 195, and will also be unresponsive to the upward movement of the lever 206. 70

If, when the parts are in normal condition, or after the train has come to rest following the conclusion of two operative cycles thereof, (as just described) the diaphragm 170' raises the bar 195 to a position higher than that shown by Figs. 13 and 14,—the flange 199 will engage the lug 205 and will thus raise the lever 172'; whereupon the train will be released and the various parts will function in the manner 80 hereinbefore more fully described in connection with Fig. 12. 75

From the foregoing it will be seen that the starting and stopping mechanism illustrated by Figs. 13, 14 and 15 is arranged 85 for operation in response to action of an extraneous force through one or another of two avenues; that the diaphragm 170', the bar 195, the springs 201 and 203, and the flanges 199 and 200 serve as translating 90 mechanism for the pressure of the liquid or gaseous force applied within the chamber 171'; and that the levers 172' and 206, and the parts carried thereby, provide two avenues through one or the other of which 95 the determining lever 60' of the starting and stopping mechanism may be moved to release the train.

Should an excessive pressure be applied to the diaphragm 170',—the projection 180 100 will prevent over-travel of the lever 172' and parts moving therewith, and the spring 201 will prevent injury to said lever or to the portions of the signaling train engaged thereby. In the event of the development 105 of an abnormally low pressure within the chamber 171', the projection carried by the lever 206 which corresponds with the projection 180 will correspondingly prevent over-travel of said lever 206, and the spring 110 203 will correspondingly prevent injury to said lever or train.

It will be evident to those skilled in this art, that, if desired, the lever 172' could be operable by one translating mechanism and 115 the lever 206 or some equivalent member could be operable by another similar translating mechanism, and that the application of this invention is not limited to the illustrations shown by the accompanying drawings and hereinbefore described; but that, in the light of the foregoing description and the accompanying drawings, said invention may readily be so applied as to be utilized under almost any combination of 120 service conditions, and requirements which have heretofore arisen or seem likely to arise in any signaling service. 125

What I claim and desire to secure by Letters Patent of the United States of America is:—

1. In a signal device; transmitting means for formulating two different signals, and operating means so constructed and arranged as to be adapted to act for a greater or less number of cycles to operate said transmitting means to formulate a signal during each cycle, said operating means arranged to render the formulation of one of such signals effective only after a predetermined number of the operative cycles thereof, in combination with an electromagnet for controlling said operating means, and circuit controlling mechanism arranged for operation by said operating means to vary responsiveness of said electromagnet to individual ones of a plurality of current paths, in an established order of selection, after various predetermined numbers of such cycles.
2. In a signal device; transmitting means for formulating a signal, and operating means so constructed and arranged as to be adapted to act for a greater or less number of cycles to operate said transmitting means to formulate a signal during each cycle, in combination with an electromagnet for controlling said operating means, independent current paths for effecting the energization of said magnet, and circuit controlling mechanism arranged for operation by said operating means to discontinue responsiveness of said magnet to one of said current paths after a predetermined number of such cycles.
3. In a signal device; transmitting means for formulating two different signals, and operating means so constructed and arranged as to be adapted to act for a greater or less number of cycles to operate said transmitting means to formulate a signal during each cycle, in combination with an electromagnet for controlling said operating means, independent current paths for effecting the energization of said magnet, and circuit controlling mechanism arranged for operation by said operating means to discontinue responsiveness of such magnet to one of said current paths and to establish responsiveness of said magnet to another current path after other predetermined numbers of such cycles.
4. In a signal device; transmitting means for formulating two different signals, and operating means so constructed and arranged as to be adapted to act for a greater or less number of cycles to operate said transmitting means to formulate a signal during each cycle, said operating means arranged to render the formulation of one of such signals effective only after a predetermined number of the operative cycles there-

of, in combination with an electromagnet 65 for controlling said operating means, independent current paths for effecting the energization of said magnet, and circuit controlling mechanism arranged for operation by said operating means to discontinue responsiveness of said magnet to one of said current paths after a further predetermined number of such cycles.

5. In a signal device; transmitting means for formulating two different signals, and operating means so constructed and arranged as to be adapted to act for a greater or less number of cycles to operate said transmitting means to formulate a signal during each cycle, said operating means arranged to render the formulation of one of such signals effective only after a predetermined number of the operative cycles thereof, in combination with an electromagnet for controlling said operating means, independent current paths for effecting the energization of said magnet, and circuit controlling mechanism arranged for operation by said operating means to discontinue responsiveness of such magnet to one of said current paths and to establish responsiveness of said magnet to another current path after other predetermined numbers of such cycles.

6. In a signal device; transmitting means for formulating two different signals, operating means so constructed and arranged as to be adapted to act for a greater or less number of cycles to operate said transmitting means to formulate a signal during each cycle, starting and stopping mechanism for said operating means, said starting and stopping mechanism adapted to be conditioned either to permit initiation of such operative cycles or to terminate the action of said operating means after any such cycle, an accumulation mechanism comprising a member movable by said operating means, said accumulation mechanism so constructed and arranged that the extent of the movement so imparted to said member will increase with the number of said operative cycles that occur without intervening stops but will not so increase when the action of said operating means is suspended between such cycles, said accumulation mechanism being arranged so that, after predetermined movement of said member, said starting and stopping mechanism will be rendered ineffective to stop said operating means until said cycles have been repeated thereby a predetermined number of times, and means operable by said movable member for rendering said starting and stopping mechanism unresponsive to said actuating means after the conclusion of such repeated cycles.

7. In a signal device; transmitting means for formulating two different signals, oper-

- ating means so constructed and arranged as to be adapted to act for a greater or less number of cycles to operate said transmitting means to formulate a signal during each 5 cycle, starting and stopping mechanism for said operating means, said starting and stopping mechanism adapted to be conditioned either to permit initiation of such operative cycles or to terminate the action of said operating 10 means after any such cycle, actuating means for said starting and stopping mechanism, said actuating means being responsive to a suitable extraneous force acting through either of two avenues of communication therewith, an accumulation mechanism comprising a member movable by said operating means, said accumulation mechanism so constructed and arranged that the extent of the movement so imparted to 15 said member will increase with the number of said operative cycles that occur without intervening stops but will not so increase when the action of said operating means is suspended between such cycles, said accumulation mechanism being arranged so that, after predetermined movement of said member, said starting and stopping mechanism will be rendered ineffective to stop said operating 20 means until said cycles have been repeated thereby a predetermined number of times, and means operable by said movable member for rendering one of said avenues ineffective after predetermined actuation of 25 said movable member.
8. In a signal device; step by step mechanism comprising a member intermittently engaged for actuation thereof in one direction and having constantly imparted thereto a tendency to restore it by movement in the other direction, and holding means for retaining actuated steps during intermissions of such engagement, the relative construction and arrangement of said mechanism member and said means being such that said means will be ineffectively conditioned during actuating steps, and said means having a tendency constantly imparted thereto for 30 effective conditioning thereof; a latch for preventing effective conditioning of said means when said latch is abnormally conditioned, the relative arrangement of said latch and said means such as to prevent abnormal positioning of said latch other than while said means is ineffectively conditioned; and a determining member so arranged that it may assume either of two positions and so formed and situated as to be engaged by said latch only when said determining member is in a certain one of its positions at a time when said holding means permits abnormal positioning of said latch. 35
9. In a signal device; step by step mechanism comprising a member intermittently engaged for actuation thereof in one direction and having constantly imparted thereto a tendency to restore it by movement in the other direction, and holding means for retaining actuated steps during intermissions of such engagement, the relative construction and arrangement of said mechanism member and said means being such that said means will be ineffectively conditioned during each of certain of such actuating steps, and said means having a tend- 40
- ency constantly imparted thereto for effective conditioning thereof; and a suitably controlled latch for said means arranged to act to defeat such tendency only while said means is ineffectively conditioned. 45
10. In a signal device; step by step mechanism comprising a member intermittently engaged for actuation thereof in one direction and having constantly imparted thereto a tendency to restore it by movement in the other direction, and holding means for retaining actuated steps during intermissions of such engagement, the relative construction and arrangement of said mechanism member and said means being such that said means will be ineffectively conditioned during actuating steps, and said means having a tendency constantly imparted thereto for effective conditioning thereof; a latch so arranged with reference to said means that it may be abnormally positioned, to thereby defeat said tendency, only while said means is ineffectively conditioned; and a determining member positioned and arranged to move into or out of the path of said latch and to be suited to prevent such abnormal positioning of said latch when in such path. 50
11. In a signal device; step by step mechanism comprising a member intermittently engaged for actuation thereof in one direction and having constantly imparted thereto a tendency to restore it by movement in the other direction, and holding means for retaining actuated steps during intermissions of such engagement, the relative construction and arrangement of said mechanism member and said means being such that said means will be ineffectively conditioned during actuating steps, and said means having a tendency constantly imparted thereto for effective conditioning thereof; a latch for preventing effective conditioning of said means when said latch is abnormally conditioned, the relative arrangement of said latch and said means such as to prevent abnormal positioning of said latch other than while said means is ineffectively conditioned; and a determining member so arranged that it may assume either of two positions and so formed and situated as to be engaged by said latch only when said determining member is in a certain one of its positions at a time when said holding means permits abnormal positioning of said latch. 55
12. In a signal device; a determining member so arranged that it may assume either of two positions step by step mechanism comprising a member intermittently engaged for actuation thereof in one direction and having constantly imparted thereto a tendency to restore it by movement in the other direction, and holding means for retaining actuated steps during intermissions of such engagement, the relative construction and arrangement of said mechanism 60

- member and said means being such that said means will be ineffectively conditioned during actuating steps, and said means having a tendency constantly imparted thereto for effective conditioning thereof; and a latch so formed and situated that its movement from the normal to the abnormal positions thereof may be obstructed by said determining member when said member is in one of its said positions, said latch so arranged with reference to said holding means that it may be abnormally positioned to thereby prevent response of said holding means to the tendency imparted thereto, only while said means is ineffectively conditioned, and so that said means will serve to hold the said latch out of the path of said determining member other than when said holding means is ineffectively conditioned.
13. In a signal device; step by step mechanism comprising a member intermittently engaged for actuation thereof in one direction and having constantly imparted thereto a tendency to restore it by movement in the other direction, and holding means for retaining actuated steps during intermissions of such engagement, the relative construction and arrangement of said mechanism member and said means being such that said means will be ineffectively conditioned during each of certain of such actuating steps, and said means having a tendency constantly imparted thereto for effective conditioning thereof; a suitably controlled latch for said means arranged to act to defeat such tendency, only while said means is ineffectively conditioned; a determining member arranged for actuation to prevent such defeating action of said latch; and actuating means for said determining member so controlled by said mechanism member as to be rendered ineffective after predetermined actuation of said mechanism member.
14. In a signal device; step by step mechanism comprising a member intermittently engaged for actuation thereof in one direction and having constantly imparted thereto a tendency to restore it by movement in the other direction, and holding means for retaining actuated steps during intermissions of such engagement, the relative construction and arrangement of said mechanism member and said means being such that said means will be ineffectively conditioned during actuating steps, and said means having a tendency constantly imparted thereto for effective conditioning thereof; a latch so arranged with reference to said means that it may be abnormally positioned, to thereby defeat said tendency, only while said means is ineffectively conditioned; and a determining member so arranged that it may assume either of two positions and so formed and situated as to be engaged by said latch only when said determining member is in a cer-
- tain one of its positions at a time when said holding means permits abnormal positioning of said latch, said latch and said mechanism member so relatively constructed and arranged that said latch will be held out of the path of said determining member when said mechanism member is in its fully restored position.
15. In a signal device; step by step mechanism comprising a member intermittently engaged for actuation thereof in one direction and having constantly imparted thereto a tendency to restore it by movement in the other direction, and holding means for retaining actuated steps during intermissions of such engagement, the relative construction and arrangement of said mechanism member and said means being such that said means will be ineffectively conditioned during actuating steps, and said means having a tendency constantly imparted thereto for effective conditioning thereof; a latch so arranged with reference to said means that it may be abnormally positioned, to thereby defeat said tendency, only while said means is ineffectively conditioned; and a determining member so arranged that it may assume either of two positions and so formed and situated as to be engaged by said latch only when said determining member is in a cer-
- tain one of its positions at a time when said holding means permits abnormal positioning of said latch, said latch and said mechanism member so relatively constructed and arranged that said latch may serve to limit the extent of the restoration movement of said mechanism member and so that when so serving, said latch will be held out of the path of said determining member.
16. In a signal device; a signaling train and step by step mechanism comprising a holding pawl and a toothed member cooperating with said pawl and intermittently engaged by said train for actuation in one direction, said member having constantly imparted thereto a tendency to move in the other direction, the teeth of said member and the cooperating end of said pawl so relatively constructed and arranged as to provide lifting and holding faces the junctions of which are so formed that said pawl will be moved, by the passing thereunder of such teeth, to a position in which the holding face of said pawl will be situated such distance outside of the paths of the holding faces of such teeth as to provide a substantial working clearance therebetween.
17. In a signal device; a signaling train and step by step mechanism comprising a holding pawl and a toothed member cooperating with said pawl and intermittently engaged by said train for actuation in one direction, said member having constantly imparted thereto a tendency to move in the other direction, one or more of the teeth of

said member being shorter than the others, the teeth of said member and the cooperating end of said pawl so relatively constructed and arranged as to provide lifting 5 and holding faces the junctions of which are so formed that said pawl will be moved, by the passing thereunder of the longer of such teeth, to a position in which the holding face of said pawl will be situated such distance 10 outside of the paths of the holding faces of all of such teeth as to provide a substantial working clearance therebetween.

18. In a signal device; a signaling train and step by step mechanism comprising a 15 holding pawl and a toothed member cooperating with said pawl and intermittently engaged by said train for actuation in one direction, said member having constantly imparted thereto a tendency to move in the 20 other direction, teeth of said member having usual lifting and holding faces of ratchet teeth, the outer ends of said holding faces being beveled so that they may act as lifting faces.

25 19. In a signal device; transmitting means for formulating two different signals and operating means so constructed and arranged as to be adapted to act for a greater or less number of cycles to operate 30 said transmitting means to formulate a signal during each cycle, in combination with a detent for said operating means, actuating means comprising avenues arranged for independent effectiveness for enabling 35 intended signal initiating means to suitably influence said detent, and controlling means operable by said operating means to suspend the effectiveness of one of said avenues after a predetermined number of the 40 operative cycles of said operating means.

20. In a signal device; transmitting means for formulating two different signals and operating means so constructed and arranged as to be adapted to act for a greater or less number of cycles to operate 45 said transmitting means to formulate a signal during each cycle, in combination with a detent for said operating means, actuating means comprising avenues arranged for independent effectiveness for enabling intended 50 signal initiating means to suitably influence said detent, and controlling means operable by said operating means to establish effectiveness of one of said avenues after a predetermined number of the operative 55 cycles of said operating means.

21. In a signal device; transmitting means for formulating two different signals and operating means so constructed and arranged as to be adapted to act for a greater or less number of cycles to operate 60 said transmitting means to formulate a signal during each cycle, in combination with a detent for said operating means, actuating means comprising avenues arranged for in-

dependent effectiveness for enabling intended signal initiating means to suitably influence said detent, and controlling means operable by said operating means to suspend the effectiveness of one of said avenues 70 and to establish the effectiveness of another one of said avenues after predetermined numbers of the operative cycles of said operating means.

22. In a signal device; transmitting 75 means for formulating two different signals, operating means so constructed and arranged as to be adapted to act for a greater or less number of cycles to operate said transmitting means to formulate a signal 80 during each cycle, a detent for said operating means, and actuating means arranged for enabling intended signal initiating means to suitably influence said detent, in combination with controlling means so constructed and arranged as to enable such actuation thereof by said operating means as to control the effectiveness of said detent, irrespective of said actuating means, after a predetermined number of the operative 85 cycles of said operating means.

23. In a signal device; transmitting means for formulating two different signals, operating means so constructed and arranged as to be adapted to act for a greater 90 or less number of cycles to operate said transmitting means to formulate a signal during each cycle, a detent for said operating means, and actuating means arranged for enabling intended signal initiating 95 means to suitably influence said detent, in combination with controlling means so constructed and arranged as to enable such actuation thereof by said operating means as to control the effectiveness of said detent, 100 irrespective of said actuating means, after a predetermined number of the operative cycles of said operating means.

24. In a signal device; transmitting means for formulating two different signals, operating means so constructed and arranged as to be adapted to act for a greater 115 or less number of cycles to operate said transmitting means to formulate a signal during each cycle, a detent for said operating means, and actuating means arranged for enabling intended signal initiating 120 means to suitably influence said detent, in combination with controlling means so constructed and arranged as to enable such actuation thereof by said operating means as to control the effectiveness of said detent, 125 irrespective of said actuating means, after a predetermined number of the operative cycles of said operating means, to thereby assure activity of such operating means for a further predetermined number of such 130 cycles.

cycles and to thereupon cause said detent to stop said operating means.

25. In a signal device; transmitting means for formulating two different signals, operating means so constructed and arranged as to be adapted to act for a greater or less number of cycles to operate said transmitting means to formulate a signal during each cycle, a detent for said 10 operating means, and actuating means arranged for enabling intended signal initiating means to suitably influence said detent, in combination with controlling means so constructed and arranged as to enable such 15 actuation thereof by said operating means as to control the effectiveness of said detent,

irrespective of said actuating means, after a predetermined number of the operative cycles of said operating means, to thereby assure activity of such operating means for 20 a further predetermined number of such cycles and to thereupon cause said detent to stop said operating means, and means for permitting actuation of said detent by said actuating means, following the completion 25 of such predetermined numbers of the operative cycles of said operating means, only after manual restoration of said controlling means.

In witness whereof, I hereunto subscribe 30 my name, this 24th day of November, 1920.

CLARENCE E. BEACH.
